UNITED STATES PATENT OFFICE.

WILLIAM G. BRITTON, OF FANWOOD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,271,127.

Specification of Letters Patent.

Patented July 2, 1918.

Application filed April 15, 1916. Serial No. 91,406.

To all whom it may concern:

Be it known that I, WILLIAM GARFIELD BRITTON, a citizen of the United States, residing at Fanwood, in the county of 5 Union and State of New Jersey, have invented certain new and useful Improvements in Telephone Systems, of which the following is a full, clear, concise, and exact description.

10 This invention relates to improvements in telephone systems, and more particularly to improvements in systems in which telephone amplifiers are employed.

The principal object of this invention is 15 to provide a system of this character wherein the various devices will be supplied with current at different respective potentials, in a manner to secure a uniform current drain throughout different sections of a current 20 source, and to maintain a nearly uniform working potential on the various current consuming circuits.

In accordance with this invention, two 25 sources of current supply are adapted to be connected, either in parallel or in series, one with the other, in the regular steps of working the system, and either through the action of a relay having marginal adjustments as to the current required for its operation, 30 or through the provision of a suitable switch resistance units are connected in series with or excluded from the current supply circuits, in order to maintain a more nearly constant working voltage on the telephone 35 devices.

This invention is illustrated diagrammatically in the accompanying drawing, in 40 which Figure 1 shows a typical telephone equipment, suitable for use at offices, in rail-road train despatching, or service of a similar nature; while Fig. 2 shows a modification thereof in which a hand switch alone is relied upon to control the association of the resistance units with the current supply 45 circuits.

In describing the features of this invention, in connection with the drawing, it will first be assumed that a message is being received at the station shown. Accordingly, 50 voice currents coming in, say from a distant station, may be traced by way of a main line conductor 1, windings 6 and 7, of a telephone amplifier 5, a condenser 10, switch-hook contacts 11, thence outward over 55 a second main line conductor 2. In order

to properly sensitize the amplifier 5, current from a positive pole formed by batteries 14 and 15, being connected in parallel one with the other by means of the contacts 17 and 18 of a switching device 16, completes circuit over a section of the main conductor 1, the windings 8 and 9 of the amplifier 5, a resistance unit 26, thence to the negative pole jointly formed by the batteries 14 and 15. The magnetism thereby set 60 up in the amplifier 5 is of such polarity relation that an armature 4 is acted upon by the voice currents through the windings 6 and 7, to execute a rocking motion on the bearing present at the centrally positioned 65 magnet pole. This rocking motion of the armature 4 causes variations of pressure on the comminuted material of a microphone 30, which, in turn, is connected in series with a primary winding 31 of a transformer 70 75 32, which series circuit is connected to receive battery current in parallel with the windings 8 and 9 of the amplifier 5. The current variations set up in the transformer winding 31 by the operation of the microphone 30 induce corresponding currents in the secondary winding 33 of this transformer, and these induced currents complete circuit through a loud-speaking telephone receiver 34 to set up the proper action 80 85 therein.

When desired, an ear-piece receiver 13 may be substituted for the loud-speaking receiver 34, by lifting the receiver 13 from its associated switch-hook, thereby separating the contacts 11 to disconnect the voice current circuit of the amplifier 5, and to close the contacts 12 which connect the receiver 13 directly across the main line conductors 1 and 2. 90

Let it now be assumed that it is desired to send a message from the station shown in the drawing, to a distant station provided with identical equipment and connected in a similar manner to the main conductors. 100 1 and 2.

First a plunger 16, usually operated for convenience as a foot switch, is depressed, thereby causing the separation of the contacts 17, 18 and 19, and the closing of the 105 contacts 20, 21, 22 and 23. Separation of the contacts 17 and 18 disconnects the batteries 14 and 15 from multiple relation, and the closing of the contacts 20 and 21 connects these batteries to form an accumula- 110

tive series, one with the other. The closing of the contacts 22 and 23 connects the secondary winding 37 of an induction coil 35 in bridge on the main conductors 1 and 2. A further circuit, closed by the contact 22, may be traced from the negative pole of the battery 15, over a resistance unit 27, a telephone transmitter 38, a primary winding 36 of the induction coil 35, the contact 22, to the positive pole of the battery 14. In this position of the connections, the transmitter circuit is supplied with current at the combined potential of the serially connected batteries 14 and 15. The polarizing circuit and the microphone circuit of the amplifier 5, however, remain connected in parallel on the battery 14, and therefore continue to operate at the same potential, irrespective of a series or parallel condition which may be present in the grouping of the batteries 14 and 15. It will be apparent that current action set up in the primary winding 36 of the induction coil 35 induces corresponding current changes in the secondary winding 37, connected in bridge on the main conductors 1 and 2. These telephone currents accordingly traverse the circuits of an amplifier at the distant station, and are there reproduced in a manner corresponding to the operations by which the receiving of a message has already been described. During the sending of a message, it is entirely optional whether the receiver 13 or the loud-speaking receiver 34 remains in circuit at the transmitting station.

In describing the service features of a voltage governing relay 25, it will be noted that during the time this relay is operated, which is the position shown in the drawing, the resistance units 26 and 27 are included in series with the respective current supply circuits of the amplifier 5, and the transmitter 38, which circuits have already been described. On the deenergization of the relay, its contacts 28 and 29, respectively, short-circuit the resistance units 26 and 27. The action which determines whether the relay 25 will either remain operated or inert, relates to the potential condition of the batteries 14 and 15. The relay is conditioned to attract the armatures thereof only on a current strength which is in excess of a predetermined number of amperes, and to remain inert in case the current is not above that strength. In event of the relay receiving sufficient strength of current to attract its armatures, they will remain attracted until the strength of current drops below another predetermined number of amperes, on which the relay is designed to permit the armatures to be retracted, thereby short-circuiting the resistances 26 and 27. In order to secure a more positive response of the relay 25, to changes of current strength therein, the contacts 19 of the foot-switch 16

connect the relay winding in a certain polarity relation across the parallel connected batteries 14 and 15. When the foot switch is operated, however, as described, for sending a message, the separation of the contacts 19 momentarily disconnects the relay, thereby permitting it to release. The following closing of the contacts 21 of the switch connects the relay winding across the battery 15, but in a polarity direction opposite to that present with its former connected position across the multiplied batteries, thereby producing magnetic flux of opposite polarity to that produced on the previous magnetization and neutralizing any residual magnetism which might, in rare instances, serve to retain the armatures attracted, even though the energizing circuit were momentarily opened at the contacts 19. In such cases neutralization of the magnetic flux will result in the armatures of the relay 25 being retracted and they will not again be attracted unless the strength of current received through the new battery connection is sufficiently great to again operate the relay.

The utility of the compensating or current regulating resistance units 26 and 27 applies to systems employing either primary batteries, secondary or storage cells, or suitable generators, and for each arrangement may be described as follows: In the case of primary batteries, it is well known that when certain types of such cells are first set up, or immediately after renewal of their elements, etc., the batteries are capable of working for a limited time at a potential in excess of that to which their pressure will soon fall, and at which they will thereafter continue to operate for a considerable period. In the case of storage cells, the variation of potential present between the time of maximum charging and the time of minimum discharging is considerable, and in the case of generators, as dynamos, it is also well known that fluctuations of voltage may take place, due to many well-known causes. In order that the current supplied to the various devices described may continue at a practically uniform strength, irrespective of the changes in potential of the source of supply which take place as described, the relay 25 is adapted to be held operated on the higher potentials, thereby inserting the resistance units 26 and 27 in the current supply circuits. When the potential of the current source falls below a predetermined pressure, the relay 25 is designed to effect the retraction of its armatures, which thereby effects short-circuiting of these compensating resistances.

The feature of automatically releasing and reversing the current polarity through the marginally conditioned relay 25 permits this compensating arrangement to be

effective on comparatively narrow margins of potential variations. When the system is installed in places wherein close supervision of batteries and other current sources is maintained, it is possible to do away with the automatic supervision provided by the relay 25, by the substitution of a hand switch 39 as shown in Fig. 2. In this event the switch 39 will ordinarily be kept in open condition 10 until supervision shows that the batteries have dropped to a predetermined current strength, whereupon the switch 39 will be closed to short-circuit the regulating resistances 26 and 27. The operation of this 15 modified system is otherwise the same as that of the system shown in Fig. 1.

In situations where it may be desirable to substitute the manually operated switch 39 for the voltage regulating relay 25, the 20 contacts 40 and 41 respectively are substituted for the contacts 28 and 29 of the relay 25 for controlling the insertion or exclusion of the resistance units 26 and 27 in the current supply circuits as described. 25 The contacts 19 and 21 are also unnecessary in a system so modified.

The present system is particularly adapted for service in situations where it is desired that a message be reproduced simultaneously at several stations, which is usually the case in announcing systems, railway train despatching service, etc. The requirements of such service is met by connecting a plurality of stations corresponding to the equipment shown in the drawing to the same line circuit, as the main conductors 1 and 2.

What is claimed is:

1. In a telephone system, a line circuit, 40 an amplifier associated therewith, a receiver operated by said amplifier, a transmitter associated with said line circuit, current sources to supply current to said amplifier and transmitter, and switching means for interchangeably connecting said sources of current in series or in parallel, one with the other.
2. In a telephone system, an amplifier, a receiver operated by said amplifier, a transmitter, sources of current to supply current to said amplifier and transmitter, switching means for connecting said sources of current either in parallel or in series, one with the other, and means for supplying current 50 to said transmitter at the added voltage of said sources of current while supplying current to said amplifier at an intermediate potential.
3. In a telephone system, a line circuit, a 60 transmitter and a receiver, an amplifier, sources of current for said system, switching means for disconnecting said transmitter and connecting said sources of current in parallel, one with the other, to supply 65 current to said amplifier; switching means

for connecting said sources of current in series, one with the other, and in turn in series with said transmitter, and derived circuit means for retaining said amplifier connected to its original potential point on 70 said sources of current.

4. In a telephone system, a line circuit, a transmitting and a receiving means associated with said line circuit, sources of current for said transmitting and receiving 75 means, and an electroresponsive means for regulating the strength of working current supplied to said transmitting and receiving means.

5. In a telephone system, a line circuit, 80 an amplifier associated therewith, and a receiver operated by said amplifier, a transmitter, sources of current for said amplifier and transmitter, means for regulating the working current of said sources of current, 85 and electroresponsive means conditioned to operate only on current in excess of a predetermined strength for controlling said current regulating means.

6. In a telephone system, a telephonic device, a circuit for said device, sources of current for said system, electro-responsive means included with said sources of current to regulate the working current supplied to said device, switching means to 90 vary the arrangement of said sources of current in said system, and means to interrupt the inclusion of said electro-responsive means with said sources of current on operation of said switching means. 100

7. In a telephone system, a telephonic device, sources of current for said system, electro-responsive means included with said sources of current to regulate the working current supplied to said device, switching 105 means to vary the arrangement of said sources of current in said system from one condition to another, and means to momentarily interrupt the inclusion of said electro-responsive means with said sources of 110 current on operation of said switching means.

8. In a telephone system, a telephonic device, a circuit for said device, sources of current for said system, electro-responsive 115 means included with said sources of current for regulating the working current supplied to said device, and switching means for interchangeably including said electroresponsive means with said sources of current 120 in different polarity directions.

9. In a telephone system, a plurality of telephonic devices, circuits for said devices, sources of current supply for said system, switching means for interchangeably connecting said sources of current either in parallel or in series, one with the other, electroresponsive means included with said sources of current for regulating the working 125 strength of current supplied to said de- 130

5 vices, and contacts controlled by said switching means for disconnecting said electro-responsive means from said sources of current supply and reconnecting it thereto in reversed polarity relation.

10 10. In a telephone system, a line circuit, an amplifier, a receiver associated with said amplifier, a transmitter for connection with the said line circuit, means to control the connection of said transmitter with said

line circuit, current sources to supply current to said amplifier and transmitter, and switching means to interchangeably connect said sources of current in series or in parallel one with the other, depending on whether or not the transmitter is connected with said line circuit. 15

In witness whereof, I hereunto subscribe my name this 14th day of April, A. D. 1916.

WILLIAM G. BRITTON.
